Kerr, Page, Cooper and Hayward.

UNITED STATES PATENT OFFICE.

OSCAR A. ROSS, OF NEW YORK, N. Y.

AEROPLANE PROPELLER OR THE LIKE.

1,402,539.

Specification of Letters Patent.

Patented Jan. 3, 1922.

Application filed September 14, 1917. Serial No. 191,438.

To all whom it may concern:

Be it known that I, OSCAR A. Ross, a citizen of the United States of America, residing at 115 Carnegie Hall, New York city, county of New York, State of New York, have invented a new and useful Improvement in Aeroplane Propellers or the like, of which the following is a specification.

This invention upon which is based my present application for Letters Patent pertains to air propellers, or screws for aeroplanes. They are employed preferably in connection with that class of aeroplanes known as the tractor type. My invention has for its more prominent objects the attainment in a more economical and effective manner of the results, or operations herein-after specified.

Primarily the purpose in view is to permit propellers to be operated at a much higher rotative speed than those now in common use. At the present time the limit of rotative speed of propellers is such that gearing is interposed between the motor and propeller to permit obtaining maximum efficiency from the motor, the motor running considerably faster than the propeller. It is evident that this gearing entails a loss of power, adds weight and is otherwise objectionable.

A further object is to furnish a shield formed with a streamline surface for the center portion of the propeller, such, that the air at the center of the propeller will be forced out into the maximum torque producing portion of the blades thereby forming a dense, compact column of air for the efficient portion of the blades to work in. It is a well known fact that with an 8 to 9 foot diameter propeller in excess of 90 per cent of the torque is obtained in the last 18 to 24 inches of the blade.

All the above and other objects sought are attained by the propeller, which for purposes of specific illustration, is shown in the accompanying drawings, in which—

Figure 1, is a plan view of my improved propeller looking at the forward end of an aeroplane.

Figure 2, is a side elevation of Figure 1.

Figure 3, is a modification of means to reinforce the propeller blade shown in Figures 1, and 2.

Figure 4, is a diagrammatic illustration of stresses in my improved form of propeller in action.

Figure 5, is likewise a diagrammatic illustration of the stresses in a propeller of common design.

None of the several parts employed in this propeller, are, or need be, of any special or unusual construction, but for a more ready understanding of the device and of its operation, a preliminary description of the construction may be apposite.

Referring to Figures 1, and 2, 1—1, are the propelling portions of the propeller blade 2. The circular sectors 3—3, may be integral or secured to the blade in any approved manner, as for example, gluing and dowelling. The hub 4, with flange 5, and bolts 6, form the unit for securing the propeller to the motor of the aeroplane.

The shield formed with a streamline surface 7, of cone like construction is secured in place by screws 8, and is notched on opposite sides to receive the blade 2. Reinforcing, or bracing members 10, are preferably fitted, glued and dowelled to the center section 2, screws 12, assisting in securing said members to the said center section. Cross members 9, serve to prevent members 10, from buckling, or springing as strains are placed upon them by springing, or bending of the propeller ends 1—1, as will more fully be hereinafter described. Screws 11, are shown as the preferable means for securing members 9, and 10, together.

Referring to Figure 3, which is a modified form of the propeller, plate 13, is of spider like construction having reinforcing ribs 14—14, and in conjunction with plate 5, and bolts 6, also forms the hub for securing the propeller to the motor. A suitable shield formed with a streamline surface not shown, is placed over the back of plate 13, to avoid eddy currents.

The operating characteristics of my improved propeller are as follows: Referring to Figure 5, the solid line S, represents the mean radial axis of a propeller of ordinary design, rotating on axis A. The distance H, represents the nominal hub diameter of the propeller and, therefore, assuming that the machine to which the propeller is attached is traveling in the direction of arrow W, the deflection of the propeller blades will be substantially in accordance with dotted line D. The dotted line T and arrows 16, represents the circumferential plane in which the maximum torque is produced by the propeller. It is evident therefore, that

with the comparatively long leverage as represented by E, that a severe bending moment is developed at X. This bending moment is developed not only in a co-axial 5 plane, as shown, but also in a circumferential plane, and these bending moments are the chief factors which prohibit the higher rotative speed of aeroplane propellers as at present employed.

10 Referring now to Figure 4, which represents the characteristics of the inventor's propeller, it is noted that the leverage F, is relatively small as compared with E, of Figure 5, therefore the bending moment at 15 Y, is much reduced for a similar rotative speed of compared propellers and obviously permits of a much higher speed with the applicant's propeller. The hub diameter in applicant's propeller is practically represented by the distance G, the center section 20 2, with reinforcing members 9, and 10, forming a rigid unyielding structure.

As stated hereinbefore, practically all the torque developed by an aeroplane propeller 25 is obtained from the outer one half of the blades. Owing to a factor known generally as the slip, said slip being due to head resistance, etc., a propeller never travels progressively at the theoretical speed calculated from its pitch. For this reason the air is always tending to be drawn into the 30 blades. This causes a partial vacuum in front of the propeller again tending to develop "churning" of the air thereby reducing 35 the efficiency and resulting torque. In my improved propeller, the shield formed

with a streamline surface 7, forces the oncoming air in the direction of arrows 15, to the outer half of the blade thereby forming a dense, compact column of air for the 40 efficient part of the blades to work on.

From all investigations conducted by the inventor it appears that the best ratio of shield formed with a streamline surface and propeller diameters are substantially as 1, 45 45 is to 2. That is the shield at its greatest diameter should be substantially one half the diameter of the propeller.

Although I have herein shown and described only certain forms of my invention, 50 it is understood various changes and modifications may be made therein without departing from the spirit of the invention.

What I claim is:—

1. In combination with an aeroplane propeller, a shield formed with a streamline surface attached thereto and means for reinforcing said propeller, said means being contained within the peripheral surface of said shield substantially as described. 55 60

2. In an aeroplane driving means, in combination: a propeller; a shield formed with a streamline surface located forwardly of the propeller; means to support the shield, and reinforcing means for the propeller located rearwardly of the shield. 65

In testimony whereof, Oscar A. Ross, has signed his name to this specification in the presence of two subscribing witnesses, this 18th day of August, 1917.

OSCAR A. ROSS.
